UNBALANCE CORRECTING AMPLIFIER
SYSTEMKurt Singer, North Hollywood, Calif., assignor to
Radio Corporation of America, a corporation of
Delaware

Application September 13, 1943, Serial No. 502,142

10 Claims. (Cl. 179—171)

This invention relates to electrical transmission systems and particularly to the automatic control of the gain or attenuation of such systems.

Electrical current transmission systems are well known, these systems generally having a linear relationship between the levels of the input and output currents. It has been found desirable, however, in certain types of transmission systems such as sound recording, radio, broadcasting, telephone communications, and public address systems, to vary the gain or attenuation, both manually and automatically, in an amount depending upon the level of the original input signals. When the output levels are varied downwardly from linearity with respect to the input levels, the system is known as a compressor, and when the output levels are varied upwardly from linearity with respect to the input levels, the system is known as an expander. Normally, compression is applied to a selected upper range of input levels which may or may not require an expander before reproduction thereof. A commercial type of a compression system, wherein an expander is not required, is disclosed and claimed in my Patent No. 2,255,683 of September 9, 1941.

The present invention involves the automatic control of the current levels being transmitted in the manner shown in my above-mentioned patent, and is directed to an improvement thereof to provide higher quality operation with less service maintenance. In the general use of such automatic level control systems, a pair of variable mu vacuum tubes connected in a push-pull relationship are employed, the signal voltages or currents to be compressed or expanded being applied to the control grids as transverse voltages, while a portion of the signal currents is rectified and applied to these grids as longitudinal voltages to vary the gain of the variable mu tubes. When the push-pull circuit is perfectly balanced, all applied longitudinal voltages will be balanced out and will not be introduced into the transverse circuit of the system and, therefore, no distortion from longitudinal voltages will result. However, it is impossible to maintain such a circuit in perfect dynamic balance at all times over the entire level range. One feature of the present invention, therefore, is to prevent longitudinal voltages from being introduced into the signal being transmitted when the push-pull circuit is dynamically unbalanced.

In compressor systems of the type shown in the above-identified patent, a rectifier is usually employed to obtain a pulsating direct current proportional to the amplitude variations of the signal

current. This pulsating current is filtered to eliminate its alternating current components, and the voltage drop obtained when this current flows through a resistance is impressed longitudinally on the control grids of the variable mu tubes. The amount of filtering permissible in the circuit is limited by the required rapidity of the control action, and, in the past, a compromise had to be made between the two. The present invention provides for the cancellation of the alternating current components of the bias control currents without additional filtering. In one modification of the invention, the control action is actually speeded up without deleterious effects.

15 The principal object of the invention, therefore, is to improve the automatic performance of a variable gain amplifier.

Another object of the invention is to provide an improved compressor circuit.

20 A further object of the invention is to provide a push-pull compressor circuit wherein any unbalance thereof does not cause the introduction of longitudinal control voltages into the transmitted signals.

25 A still further object of the invention is to provide an automatic variable gain amplifier circuit wherein the longitudinal alternating current components are neutralized in the common portion of the grid-cathode and anode-cathode circuits.

30 Although the novel features which are believed to be characteristic of this invention will be pointed out with particularity in the appended claims, the manner of its organization and the mode of 35 its operation will be better understood by referring to the following description read in conjunction with the accompanying drawings forming a part hereof, in which:

Fig. 1 is a schematic diagram of a variable gain 40 amplifier embodying one modification of the invention, and

Fig. 2 is a schematic diagram of the variable gain amplifier of Fig. 1 embodying a second modification of the invention.

45 Referring now to both figures wherein like elements are designated by the same numeral, a signal is impressed upon the primary of transformer 5 across the secondary of which are terminating resistances 6 and 7. The secondary is connected to the control grids of variable mu tubes 9 and 10 connected in a push-pull relationship, the anodes of the tubes being connected to a resistance-capacity network coupling the tubes 9 and 10 to triode amplifier tubes 23 and 24. The coupling 50 network comprises condensers 12 and 13 and re-

sitors 14, 15, 16, and 17. A potentiometer for balancing the circuit comprising resistors 19, 20, and 21 and condenser 22 is connected across the anodes of tubes 9 and 10.

The output circuit of amplifier tubes 23 and 24 is connected to the primary of transformer 25, the secondary feeding the output circuit which may be either another amplifier, a recorder, a loud speaker, a modulator, or similar load. The secondary of transformer 25 is also connected by conductors 26 to the primary of a transformer 27. The secondary of transformer 27 is connected over potentiometer 28 to the input of an alternating current amplifier 30, the output of which is coupled through transformer 31 to a full wave rectifier 32. Anode potentials are supplied to the respective tubes from the plus and minus B terminals over conductors 70 and 71 and resistors 38 and 52, these resistors being shunted by bypass condensers 39 and 37, respectively. A bypass condenser 50 is also provided. Resistors 42 and 43 form a voltage divider for obtaining the proper screen grid voltage for the tubes 9 and 10, condenser 51 serving as a bypass condenser.

Referring now to Fig. 1, the static operating bias for the tubes 9 and 10 is obtained by the voltage drop produced by the plate current flowing through inductance 45 and resistor 46, the resistor 46 representing the direct current resistance of the inductance 45 and any additional resistance necessary to provide the proper bias. These elements are in the common portion of the plate-cathode circuit and the grid-cathode circuit, the latter circuit being from the control grids of tubes 9 and 10 over the secondary of transformer 5 and terminating resistors 6 and 7, conductor 64, resistor 40, conductor 68, inductance 45, and resistor 46 to the cathodes of the tubes 9 and 10. Thus, any current change in the resistor 40 will vary the bias on the control grids of tubes 9 and 10 and vary the gain thereof. All currents flowing through resistor 40 are derived from the rectifier 32, the rectified current flow from the rectifier 32 being from the cathodes of the rectifier through resistors 35 and 36 shunted by condenser 33 of a potentiometer made up of resistors 34, 35, and 36, the connection to resistor 36 being variable to provide the proper level at which compression occurs as described in detail in my above-mentioned patent, through resistor 40 and the secondary of transformer 31 to the anodes of the rectifier 32.

Shunted across the resistor 40 is a condenser 47, the resistance of resistors 35 and 36, the resistance of the secondary of transformer 31, and the internal resistance of the rectifier 32, determining the rate of charge of this condenser and the speed of operation of the gain change upon an increase in signal current. The resistor 40 determines the time of discharge of condenser 47 because of the high resistance of the rectifier 32, and consequently the rate at which the gain is restored to its previous value upon a decrease or cessation of the signal currents. The time of discharge of condenser 47 is considerably greater than the time of charge because of the high value of the discharge control resistor 40 with respect to the resistance in the charging circuit.

As pointed out above, since it is impossible to obtain a perfect dynamic balance in both halves of the push-pull circuit at all signal levels and the fact that the best balance obtainable does not remain so during operation, it is necessary to obtain neutralization of the longitudinal components if they are not to be introduced into the

signal circuit. In the past, these types of compressor circuits have employed in the common portion of the grid-cathode and plate-cathode circuits, a resistor of a value sufficient to provide the proper static bias for the variable mu.tubes. In other words, in place of the elements 45 and 46 shown in Fig. 1, a resistor has been used of a value of approximately 2200 ohms. This resistor provided a certain amount of feedback voltage, but an entirely insufficient amount to prevent the introduction of the longitudinal currents into the signal when the push-pull circuit became out of balance to any appreciable degree. To permit obtaining sufficient feedback voltage, the present invention utilizes an inductance such as shown at 45, and since this inductance may not include sufficient direct current resistance to provide the proper static bias, a building out resistor might have to be added. The value of inductance 45 is determined by the amount of feedback action desired, which is a value to provide the proper neutralizing feedback voltage during gain changes taking place at a rate at which "thump" is introduced. This neutralizing action is also effective for the alternating current components from the rectifier 32. These "thump" and alternating current components would not, of course, be introduced in a true dynamically balanced push-pull circuit without feedback. However, this feedback arrangement permits the circuit to function as though it were such a true dynamically balanced circuit. Thus, by the simple expedient of substituting an inductance for the normal static biasing resistor, the compressor circuit will tolerate a considerable dynamic unbalance without interference with its operation.

Although the modification shown in Fig. 1 and described above permits considerable unbalance of the variable gain circuit without deleterious effects, it does not permit of any increase in the speed of operation of the gain control action, and might even increase the acting time. To provide a system, therefore, with the same degree of neutralization as provided by the inductance 45, and which simultaneously permits faster operation than heretofore, the modification shown in Fig. 2 is used. In this modification only a resistor 61 is substituted for the normal resistor shown in my above-mentioned patent, the resistance of resistor 61 being in the neighborhood of 25,000 ohms, as compared with the normal resistance of 2200 ohms. It is obvious that the voltage drop across such a high resistor will provide too high a static bias voltage on the tubes 9 and 10. To permit the use of such a high resistance and simultaneously obtain the correct static bias, a certain amount of positive potential from the anode voltage source is applied to the grids to neutralize that portion of the direct current voltage drop above the required value.

In Fig. 2, therefore, a variable resistor element 62 is added to the potentiometer connected across the anode voltage supply, the variable connection controlling the value of the positive voltage applied to the grids of tubes 9 and 10 over conductor 65, resistor 60, and resistor 62. Thus, the modification in Fig. 2 has no tendency to slow up the gain control action of the compressor and in fact permits a more rapid gain change without additional filtering since the feedback voltage is obtained across a pure resistance. The modification does require, however, the use of an additional circuit to off-set the high positive bias applied by the high resistance to the cathodes of the variable mu tubes.

The above circuit modifications have proved to have decided advantages over the circuit shown in my above-mentioned patent in preventing the introduction of longitudinal currents into the signal when the push-pull circuit is considerably unbalanced dynamically, the modification of Fig. 2 actually permitting a speeding up of the control action of the system without additional filtering. Such compressors as described above, have operated over long periods without requiring rebalancing.

I claim as my invention:

1. A system for obtaining a rapid control action of a variable gain amplifier comprising a push-pull circuit, a pair of vacuum tubes in said circuit, means for obtaining a direct current proportional to the variations in amplitude of a signal being transmitted by said tubes, a grid-cathode circuit for said tubes, a plate-cathode circuit for said tubes, said circuits having a common portion, means for obtaining a voltage proportional to the variations of said direct current for varying the gain of said tubes, said means being connected in said grid-cathode circuit, filter means for said direct current insufficient to completely eliminate alternating current components of said direct current and means in said common circuit portion for neutralizing said alternating current components introduced into said push-pull circuit due to the unbalance thereof.

2. A variable gain amplifier system in accordance with claim 1 in which said last mentioned means comprises an inductance for producing a feedback neutralizing voltage and a static bias voltage for said tubes.

3. A variable gain amplifier system in accordance with claim 1 in which said last mentioned means comprises a resistor for producing a neutralizing voltage, additional means being provided for neutralizing the excessive positive bias on the cathodes of said tubes produced by said resistor.

4. A variable gain amplifier system having a rapid control action comprising an incoming line and an outgoing line, a push-pull circuit intermediate said lines including a pair of vacuum tubes, a rectifier for rectifying a portion of the signal being transmitted by said tubes, a filter in the output of said rectifier for obtaining a voltage in accordance with the variations in amplitude of the rectified current, said filter providing a rapid control action upon increases in amplitude of said signal but insufficient filtering to eliminate the alternating current components from said rectified current, an anode-cathode circuit for said tubes, a grid-cathode circuit for said tubes including said filter, said circuits having a circuit portion common to each, and means in said common circuit portion for neutralizing the alternating current components present in said rectified current and alternating current components produced in said plate-cathode circuit during sudden gain changes when said push-pull circuit is unbalanced.

5. A variable gain amplifier system in accordance with claim 4 in which said last mentioned means comprises an inductance of such a value

as to provide a neutralizing voltage in said grid-anode circuit, said voltage being caused by currents in said plate-cathode circuit due to an unbalance of said push-pull circuit.

6. A variable gain amplifier circuit in accordance with claim 4 in which said last mentioned means comprises a resistor having a sufficiently high value of resistance to produce a neutralizing feedback voltage for the unbalance currents in the plate-anode circuit of said tubes, and in which means are provided for neutralizing the high positive bias on the cathodes of said tubes produced by plate current flow through said high resistance.

7. A variable gain signal amplifier having a fast control action during increases in amplitude of a signal transmitted thereby comprising a pair of vacuum tubes each having input electrodes and an associated input circuit and output electrodes and an associated output circuit, said input and output circuits being connected to form a push-pull amplifier system, means for applying to the input electrodes of said tubes a signal to be amplified, a rectifier for obtaining a direct current proportional to the amplitude variations of said signal, a filter for said direct current, said filter permitting said direct current to rise rapidly, but contain undesirable alternating current components, means for applying to the input electrodes of said tubes a voltage derived from said direct current to vary the gain of said tubes in accordance with the amplitude of said signal, means for balancing said push-pull system, and means in said gain varying circuit of said tubes for maintaining said system in effective balance to eliminate the alternating current components in said direct current, and last mentioned means comprising an impedance the value thereof being such as to provide a neutralizing voltage to the input electrodes of said tubes in proportion to the currents in said output circuit produced by an actual unbalance of said system.

8. A signal amplifier in accordance with claim 7 in which said impedance is an inductance.

9. A signal amplifier in accordance with claim 7 in which said impedance is a relatively high resistance.

10. A circuit system for obtaining a fast acting control for the gain of a variable gain amplifier having a pair of vacuum tubes in a push-pull circuit and a rectifier for rectifying a portion of the signal currents for obtaining a direct current, said circuit system comprising a filter in the output of said rectifier, said filter including a resistor through which rectified current flows for varying the gain of said tubes in accordance with the variations in amplitude of said signal, said filter permitting the output current of said rectifier to rise rapidly but to contain alternating current components, an anode-cathode circuit for said tubes, a grid-cathode circuit for said tubes, said anode-cathode circuit and said grid-cathode circuit having a common portion, and means positioned in said common portion to provide neutralization of said alternating current components introduced into said common portion from said filter resistor.
